ABSTRACT

Disclosed herein is an exemplary supplemental heating system including a hydrodynamic heater and a heat exchanger. The hydrodynamic heater includes a hydrodynamic chamber disposed within an interior cavity of the hydrodynamic heater. The hydrodynamic chamber is operable for selectively heating a fluid present within the hydrodynamic chamber when the heating apparatus is connected to a fluid supply source. The hydrodynamic heater includes an inlet port fluidly connected to a discharge port of the heat exchanger, and a discharge port fluidly connected to an inlet port of the heat exchanger. The heat exchanger includes a heat exchanger core disposed within an interior cavity of the heat exchanger. A wall at least partially defines the interior cavity of the hydrodynamic heater and the interior cavity of the heat exchanger.

LIQUID HEAT GENERATOR WITH
INTEGRAL HEAT EXCHANGERCROSS REFERENCE TO RELATED
APPLICATIONS

This application claims priority to U.S. provisional patent application Ser. No. 61/084,517, filed on Jul. 29, 2008, the disclosures of which are incorporated herein by reference in its entirety.

BACKGROUND

Conventional automotive vehicles, such as automobiles, trucks and buses, typically include a heating system for supplying warm air to a passenger compartment of the vehicle. The heating system includes a control system that allows a vehicle operator to regulate the quantity and/or temperature of air delivered to the passenger compartment so as to achieve a desired air temperature within the passenger compartment. Cooling fluid from the vehicle's engine cooling system is commonly used as a source of heat for heating the air delivered to the passenger compartment.

The heating system typically includes a heat exchanger fluidly connected to the vehicle's engine cooling system. Warm cooling fluid from the engine cooling system passes through the heat exchanger where it gives up heat to a cool air supply flowing through the heating system. The heat energy transferred from the warm cooling fluid to the cool air supply causes the temperature of the air to rise. The heated air is discharged into the passenger compartment to warm the interior of the vehicle to a desired air temperature.

The vehicle's engine cooling system provides a convenient source of heat for heating the vehicle's passenger compartment. One disadvantage of using the engine cooling fluid as a heat source, however, is that there may be a significant delay between when the vehicle's engine is first started and when the heating system begins supplying air at a preferred temperature. This may occur, for example, when the vehicle is operated in very cold ambient conditions or has sat idle for a period of time. The delay is due to the cooling fluid being at substantially the same temperature as the air flowing through the heating system and into the passenger compartment when the engine is first started. As the engine continues to operate, a portion of the heat generated as a byproduct of combusting a mixture of fuel and air in the engine cylinders is transferred to the cooling fluid, causing the temperature of the cooling fluid to rise. Since, the temperature of the air discharged from the heating system is a function of the temperature of the cooling fluid passing through the heat exchanger, the heating system will generally produce proportionally less heat while the engine cooling fluid is warming up than when the cooling fluid is at a desired operating temperature. Thus, there may be an extended period of time between when the vehicle's engine is first started and when the heating system begins producing air at an acceptable temperature level. The time it takes for this to occur will vary depending on various factors, including the initial temperature of the cooling fluid and the initial temperature of the air being heated. It is preferable that the temperature of the cooling fluid reach its desired operating temperature as quickly as possible.

Another potential limitation of using the engine cooling fluid as a heat source for the vehicle's heating system is that under certain operating conditions the engine may not be rejecting sufficient heat to the cooling fluid to enable the air stream from the vehicle's heating system to achieve a desired temperature. This may occur, for example, when operating a

2

vehicle with a very efficient engine under a low load condition or in conditions where the outside ambient temperature is unusually cold. Both of these conditions reduce the amount of heat that needs to be transferred from the engine to the cooling fluid to maintain a desired engine operating temperature. This results in less heat energy available for heating the air flowing through the vehicle's heating system.

BRIEF DESCRIPTION OF THE DRAWINGS

10

FIG. 1 is a rear perspective view of an exemplary supplemental heating system having an integrated heat exchanger;

FIG. 2 is an exploded view of the exemplary supplemental heating system;

15

FIG. 3 is a partially sectioned side elevational view of the exemplary supplemental heating system, with a manifold removed;

FIG. 4 is a rear perspective view of a heater core employed with the exemplary supplemental heating system;

20

FIG. 5 is a rear partial sectional view of the exemplary supplemental heating system;

FIG. 6 is a side partial sectional view of the heater core employed with the exemplary heating system;

25

FIG. 7 is a top partial sectional view of the heater core employed with the exemplary supplemental heating system

FIG. 8 is partially sectioned rear perspective view of the exemplary supplemental heating system, with the manifold removed; and

30

FIG. 9 is schematic depiction of the exemplary supplemental heating system.

DETAILED DESCRIPTION

Referring now to the discussion that follows and also to the drawings, illustrative approaches to the disclosed systems and methods are shown in detail. Although the drawings represent some possible approaches, the drawings are not necessarily to scale and certain features may be exaggerated, removed, or partially sectioned to better illustrate and explain the disclosed device. Further, the descriptions set forth herein are not intended to be exhaustive or otherwise limit or restrict the claims to the precise forms and configurations shown in the drawings and disclosed in the following detailed description.

45

FIGS. 1 and 2 illustrate an exemplary supplemental heating system 20 that may be fluidly connected, for example, to an automotive cooling system, for supplying heat to warm a passenger compartment of the vehicle. Supplemental heating system 20 may include a hydrodynamic heater 22 operable for heating a fluid passing through the hydrodynamic heater. Examples of hydrodynamic heaters that may be employed with supplemental heating system 20 are disclosed in U.S. Pat. No. 5,683,031, entitled Liquid Heat Generator, which issued to Sanger on Nov. 4, 1997; U.S. application Ser. No. 11/068,285, entitled Vehicle Supplemental Heating System, which was filed on Feb. 28, 2005 and published as US 2005/0205682 on Sep. 22, 2005; and U.S. application Ser. No. 11/620,682, entitled Vehicle Supplemental Heating system, which was filed on Jan. 7, 2007 and published as US 2008/0060375 on Mar. 13, 2008, each of which is incorporated herein by reference in their entirety. Attached to hydrodynamic heater 22 is a heat exchanger 24. Supplemental heating system 20 may also include a manifold 26 for selectively controlling the distribution of fluid between hydrodynamic heater 22 and heat exchanger 24.

50

Referring also to FIG. 9, which is a schematic illustration of supplemental heating system 20, hydrodynamic heater 22

55

is a housing 28 containing a pump 30 and a valve 32. A fluid line 34 is connected to the pump 30 and passes through a tube 36 to the hydrodynamic heater 22. A tube 38 is connected to the hydrodynamic heater 22 and passes through a tube 40 to the heat exchanger 24. A tube 42 is connected to the heat exchanger 24 and passes through a tube 44 to the manifold 26. A tube 46 is connected to the manifold 26 and passes through a tube 48 to the pump 30. A valve 50 is connected to the tube 46 between the manifold 26 and the pump 30.

60

FIG. 9 also shows a tube 52 connected to the tube 46 between the manifold 26 and the pump 30. The tube 52 is connected to a valve 54, which is connected to a tube 56. The tube 56 is connected to a tube 58, which is connected to a tube 60. The tube 60 is connected to a tube 62, which is connected to a tube 64. The tube 64 is connected to a tube 66, which is connected to a tube 68. The tube 68 is connected to a tube 70, which is connected to a tube 72. The tube 72 is connected to a tube 74, which is connected to a tube 76. The tube 76 is connected to a tube 78, which is connected to a tube 80. The tube 80 is connected to a tube 82, which is connected to a tube 84. The tube 84 is connected to a tube 86, which is connected to a tube 88. The tube 88 is connected to a tube 90, which is connected to a tube 92. The tube 92 is connected to a tube 94, which is connected to a tube 96. The tube 96 is connected to a tube 98, which is connected to a tube 100. The tube 100 is connected to a tube 102, which is connected to a tube 104. The tube 104 is connected to a tube 106, which is connected to a tube 108. The tube 108 is connected to a tube 110, which is connected to a tube 112. The tube 112 is connected to a tube 114, which is connected to a tube 116. The tube 116 is connected to a tube 118, which is connected to a tube 120. The tube 120 is connected to a tube 122, which is connected to a tube 124. The tube 124 is connected to a tube 126, which is connected to a tube 128. The tube 128 is connected to a tube 130, which is connected to a tube 132. The tube 132 is connected to a tube 134, which is connected to a tube 136. The tube 136 is connected to a tube 138, which is connected to a tube 140. The tube 140 is connected to a tube 142, which is connected to a tube 144. The tube 144 is connected to a tube 146, which is connected to a tube 148. The tube 148 is connected to a tube 150, which is connected to a tube 152. The tube 152 is connected to a tube 154, which is connected to a tube 156. The tube 156 is connected to a tube 158, which is connected to a tube 160. The tube 160 is connected to a tube 162, which is connected to a tube 164. The tube 164 is connected to a tube 166, which is connected to a tube 168. The tube 168 is connected to a tube 170, which is connected to a tube 172. The tube 172 is connected to a tube 174, which is connected to a tube 176. The tube 176 is connected to a tube 178, which is connected to a tube 180. The tube 180 is connected to a tube 182, which is connected to a tube 184. The tube 184 is connected to a tube 186, which is connected to a tube 188. The tube 188 is connected to a tube 190, which is connected to a tube 192. The tube 192 is connected to a tube 194, which is connected to a tube 196. The tube 196 is connected to a tube 198, which is connected to a tube 200. The tube 200 is connected to a tube 202, which is connected to a tube 204. The tube 204 is connected to a tube 206, which is connected to a tube 208. The tube 208 is connected to a tube 210, which is connected to a tube 212. The tube 212 is connected to a tube 214, which is connected to a tube 216. The tube 216 is connected to a tube 218, which is connected to a tube 220. The tube 220 is connected to a tube 222, which is connected to a tube 224. The tube 224 is connected to a tube 226, which is connected to a tube 228. The tube 228 is connected to a tube 230, which is connected to a tube 232. The tube 232 is connected to a tube 234, which is connected to a tube 236. The tube 236 is connected to a tube 238, which is connected to a tube 240. The tube 240 is connected to a tube 242, which is connected to a tube 244. The tube 244 is connected to a tube 246, which is connected to a tube 248. The tube 248 is connected to a tube 250, which is connected to a tube 252. The tube 252 is connected to a tube 254, which is connected to a tube 256. The tube 256 is connected to a tube 258, which is connected to a tube 260. The tube 260 is connected to a tube 262, which is connected to a tube 264. The tube 264 is connected to a tube 266, which is connected to a tube 268. The tube 268 is connected to a tube 270, which is connected to a tube 272. The tube 272 is connected to a tube 274, which is connected to a tube 276. The tube 276 is connected to a tube 278, which is connected to a tube 280. The tube 280 is connected to a tube 282, which is connected to a tube 284. The tube 284 is connected to a tube 286, which is connected to a tube 288. The tube 288 is connected to a tube 290, which is connected to a tube 292. The tube 292 is connected to a tube 294, which is connected to a tube 296. The tube 296 is connected to a tube 298, which is connected to a tube 300. The tube 300 is connected to a tube 302, which is connected to a tube 304. The tube 304 is connected to a tube 306, which is connected to a tube 308. The tube 308 is connected to a tube 310, which is connected to a tube 312. The tube 312 is connected to a tube 314, which is connected to a tube 316. The tube 316 is connected to a tube 318, which is connected to a tube 320. The tube 320 is connected to a tube 322, which is connected to a tube 324. The tube 324 is connected to a tube 326, which is connected to a tube 328. The tube 328 is connected to a tube 330, which is connected to a tube 332. The tube 332 is connected to a tube 334, which is connected to a tube 336. The tube 336 is connected to a tube 338, which is connected to a tube 340. The tube 340 is connected to a tube 342, which is connected to a tube 344. The tube 344 is connected to a tube 346, which is connected to a tube 348. The tube 348 is connected to a tube 350, which is connected to a tube 352. The tube 352 is connected to a tube 354, which is connected to a tube 356. The tube 356 is connected to a tube 358, which is connected to a tube 360. The tube 360 is connected to a tube 362, which is connected to a tube 364. The tube 364 is connected to a tube 366, which is connected to a tube 368. The tube 368 is connected to a tube 370, which is connected to a tube 372. The tube 372 is connected to a tube 374, which is connected to a tube 376. The tube 376 is connected to a tube 378, which is connected to a tube 380. The tube 380 is connected to a tube 382, which is connected to a tube 384. The tube 384 is connected to a tube 386, which is connected to a tube 388. The tube 388 is connected to a tube 390, which is connected to a tube 392. The tube 392 is connected to a tube 394, which is connected to a tube 396. The tube 396 is connected to a tube 398, which is connected to a tube 400. The tube 400 is connected to a tube 402, which is connected to a tube 404. The tube 404 is connected to a tube 406, which is connected to a tube 408. The tube 408 is connected to a tube 410, which is connected to a tube 412. The tube 412 is connected to a tube 414, which is connected to a tube 416. The tube 416 is connected to a tube 418, which is connected to a tube 420. The tube 420 is connected to a tube 422, which is connected to a tube 424. The tube 424 is connected to a tube 426, which is connected to a tube 428. The tube 428 is connected to a tube 430, which is connected to a tube 432. The tube 432 is connected to a tube 434, which is connected to a tube 436. The tube 436 is connected to a tube 438, which is connected to a tube 440. The tube 440 is connected to a tube 442, which is connected to a tube 444. The tube 444 is connected to a tube 446, which is connected to a tube 448. The tube 448 is connected to a tube 450, which is connected to a tube 452. The tube 452 is connected to a tube 454, which is connected to a tube 456. The tube 456 is connected to a tube 458, which is connected to a tube 460. The tube 460 is connected to a tube 462, which is connected to a tube 464. The tube 464 is connected to a tube 466, which is connected to a tube 468. The tube 468 is connected to a tube 470, which is connected to a tube 472. The tube 472 is connected to a tube 474, which is connected to a tube 476. The tube 476 is connected to a tube 478, which is connected to a tube 480. The tube 480 is connected to a tube 482, which is connected to a tube 484. The tube 484 is connected to a tube 486, which is connected to a tube 488. The tube 488 is connected to a tube 490, which is connected to a tube 492. The tube 492 is connected to a tube 494, which is connected to a tube 496. The tube 496 is connected to a tube 498, which is connected to a tube 500. The tube 500 is connected to a tube 502, which is connected to a tube 504. The tube 504 is connected to a tube 506, which is connected to a tube 508. The tube 508 is connected to a tube 510, which is connected to a tube 512. The tube 512 is connected to a tube 514, which is connected to a tube 516. The tube 516 is connected to a tube 518, which is connected to a tube 520. The tube 520 is connected to a tube 522, which is connected to a tube 524. The tube 524 is connected to a tube 526, which is connected to a tube 528. The tube 528 is connected to a tube 530, which is connected to a tube 532. The tube 532 is connected to a tube 534, which is connected to a tube 536. The tube 536 is connected to a tube 538, which is connected to a tube 540. The tube 540 is connected to a tube 542, which is connected to a tube 544. The tube 544 is connected to a tube 546, which is connected to a tube 548. The tube 548 is connected to a tube 550, which is connected to a tube 552. The tube 552 is connected to a tube 554, which is connected to a tube 556. The tube 556 is connected to a tube 558, which is connected to a tube 560. The tube 560 is connected to a tube 562, which is connected to a tube 564. The tube 564 is connected to a tube 566, which is connected to a tube 568. The tube 568 is connected to a tube 570, which is connected to a tube 572. The tube 572 is connected to a tube 574, which is connected to a tube 576. The tube 576 is connected to a tube 578, which is connected to a tube 580. The tube 580 is connected to a tube 582, which is connected to a tube 584. The tube 584 is connected to a tube 586, which is connected to a tube 588. The tube 588 is connected to a tube 590, which is connected to a tube 592. The tube 592 is connected to a tube 594, which is connected to a tube 596. The tube 596 is connected to a tube 598, which is connected to a tube 600. The tube 600 is connected to a tube 602, which is connected to a tube 604. The tube 604 is connected to a tube 606, which is connected to a tube 608. The tube 608 is connected to a tube 610, which is connected to a tube 612. The tube 612 is connected to a tube 614, which is connected to a tube 616. The tube 616 is connected to a tube 618, which is connected to a tube 620. The tube 620 is connected to a tube 622, which is connected to a tube 624. The tube 624 is connected to a tube 626, which is connected to a tube 628. The tube 628 is connected to a tube 630, which is connected to a tube 632. The tube 632 is connected to a tube 634, which is connected to a tube 636. The tube 636 is connected to a tube 638, which is connected to a tube 640. The tube 640 is connected to a tube 642, which is connected to a tube 644. The tube 644 is connected to a tube 646, which is connected to a tube 648. The tube 648 is connected to a tube 650, which is connected to a tube 652. The tube 652 is connected to a tube 654, which is connected to a tube 656. The tube 656 is connected to a tube 658, which is connected to a tube 660. The tube 660 is connected to a tube 662, which is connected to a tube 664. The tube 664 is connected to a tube 666, which is connected to a tube 668. The tube 668 is connected to a tube 670, which is connected to a tube 672. The tube 672 is connected to a tube 674, which is connected to a tube 676. The tube 676 is connected to a tube 678, which is connected to a tube 680. The tube 680 is connected to a tube 682, which is connected to a tube 684. The tube 684 is connected to a tube 686, which is connected to a tube 688. The tube 688 is connected to a tube 690, which is connected to a tube 692. The tube 692 is connected to a tube 694, which is connected to a tube 696. The tube 696 is connected to a tube 698, which is connected to a tube 700. The tube 700 is connected to a tube 702, which is connected to a tube 704. The tube 704 is connected to a tube 706, which is connected to a tube 708. The tube 708 is connected to a tube 710, which is connected to a tube 712. The tube 712 is connected to a tube 714, which is connected to a tube 716. The tube 716 is connected to a tube 718, which is connected to a tube 720. The tube 720 is connected to a tube 722, which is connected to a tube 724. The tube 724 is connected to a tube 726, which is connected to a tube 728. The tube 728 is connected to a tube 730, which is connected to a tube 732. The tube 732 is connected to a tube 734, which is connected to a tube 736. The tube 736 is connected to a tube 738, which is connected to a tube 740. The tube 740 is connected to a tube 742, which is connected to a tube 744. The tube 744 is connected to a tube 746, which is connected to a tube 748. The tube 748 is connected to a tube 750, which is connected to a tube 752. The tube 752 is connected to a tube 754, which is connected to a tube 756. The tube 756 is connected to a tube 758, which is connected to a tube 760. The tube 760 is connected to a tube 762, which is connected to a tube 764. The tube 764 is connected to a tube 766, which is connected to a tube 768. The tube 768 is connected to a tube 770, which is connected to a tube 772. The tube 772 is connected to a tube 774, which is connected to a tube 776. The tube 776 is connected to a tube 778, which is connected to a tube 780. The tube 780 is connected to a tube 782, which is connected to a tube 784. The tube 784 is connected to a tube 786, which is connected to a tube 788. The tube 788 is connected to a tube 790, which is connected to a tube 792. The tube 792 is connected to a tube 794, which is connected to a tube 796. The tube 796 is connected to a tube 798, which is connected to a tube 800. The tube 800 is connected to a tube 802, which is connected to a tube 804. The tube 804 is connected to a tube 806, which is connected to a tube 808. The tube 808 is connected to a tube 810, which is connected to a tube 812. The tube 812 is connected to a tube 814, which is connected to a tube 816. The tube 816 is connected to a tube 818, which is connected to a tube 820. The tube 820 is connected to a tube 822, which is connected to a tube 824. The tube 824 is connected to a tube 826, which is connected to a tube 828. The tube 828 is connected to a tube 830, which is connected to a tube 832. The tube 832 is connected to a tube 834, which is connected to a tube 836. The tube 836 is connected to a tube 838, which is connected to a tube 840. The tube 840 is connected to a tube 842, which is connected to a tube 844. The tube 844 is connected to a tube 846, which is connected to a tube 848. The tube 848 is connected to a tube 850, which is connected to a tube 852. The tube 852 is connected to a tube 854, which is connected to a tube 856. The tube 856 is connected to a tube 858, which is connected to a tube 860. The tube 860 is connected to a tube 862, which is connected to a tube 864. The tube 864 is connected to a tube 866, which is connected to a tube 868. The tube 868 is connected to a tube 870, which is connected to a tube 872. The tube 872 is connected to a tube 874, which is connected to a tube 876. The tube 876 is connected to a tube 878, which is connected to a tube 880. The tube 880 is connected to a tube 882, which is connected to a tube 884. The tube 884 is connected to a tube 886, which is connected to a tube 888. The tube 888 is connected to a tube 890, which is connected to a tube 892. The tube 892 is connected to a tube 894, which is connected to a tube 896. The tube 896 is connected to a tube 898, which is connected to a tube 900. The tube 900 is connected to a tube 902, which is connected to a tube 904. The tube 904 is connected to a tube 906, which is connected to a tube 908. The tube 908 is connected to a tube 910, which is connected to a tube 912. The tube 912 is connected to a tube 914, which is connected to a tube 916. The tube 916 is connected to a tube 918, which is connected to a tube 920. The tube 920 is connected to a tube 922, which is connected to a tube 924. The tube 924 is connected to a tube 926, which is connected to a tube 928. The tube 928 is connected to a tube 930, which is connected to a tube 932. The tube 932 is connected to a tube 934, which is connected to a tube 936. The tube 936 is connected to a tube 938, which is connected to a tube 940. The tube 940 is connected to a tube 942, which is connected to a tube 944. The tube 944 is connected to a tube 946, which is connected to a tube 948. The tube 948 is connected to a tube 950, which is connected to a tube 952. The tube 952 is connected to a tube 954, which is connected to a tube 956. The tube 956 is connected to a tube 958, which is connected to a tube 960. The tube 960 is connected to a tube 962, which is connected to a tube 964. The tube 964 is connected to a tube 966, which is connected to a tube 968. The tube 968 is connected to a tube 970, which is connected to a tube 972. The tube 972 is connected to a tube 974, which is connected to a tube 976. The tube 976 is connected to a tube 978, which is connected to a tube 980. The tube 980 is connected to a tube 982, which is connected to a tube 984. The tube 984 is connected to a tube 986, which is connected to a tube 988. The tube 988 is connected to a tube 990, which is connected to a tube 992. The tube 992 is connected to a tube 994, which is connected to a tube 996. The tube 996 is connected to a tube 998, which is connected to a tube 1000. The tube 1000 is connected to a tube 1002, which is connected to a tube 1004. The tube 1004 is connected to a tube 1006, which is connected to a tube 1008. The tube 1008 is connected to a tube 1010, which is connected to a tube 1012. The tube 1012 is connected to a tube 1014, which is connected to a tube 1016. The tube 1016 is connected to a tube 1018, which is connected to a tube 1020. The tube 1020 is connected to a tube 1022, which is connected to a tube 1024. The tube 1024 is connected to a tube 1026, which is connected to a tube 1028. The tube 1028 is connected to a tube 1030, which is connected to a tube 1032. The tube 1032 is connected to a tube 1034, which is connected to a tube 1036. The tube 1036 is connected to a tube 1038, which is connected to a tube 1040. The tube 1040 is connected to a tube 1042, which is connected to a tube 1044. The tube 1044 is connected to a tube 1046, which is connected to a tube 1048. The tube 1048 is connected to a tube 1050, which is connected to a tube 1052. The tube 1052 is connected to a tube 1054, which is connected to a tube 1056. The tube 1056 is connected to a tube 1058, which is connected to a tube 1060. The tube 1060 is connected to a tube 1062, which is connected to a tube 1064. The tube 1064 is connected to a tube 1066, which is connected to a tube 1068. The tube 1068 is connected to a tube 1070, which is connected to a tube 1072. The tube 1072 is connected to a tube 1074, which is connected to a tube 1076. The tube 1076 is connected to a tube 1078, which is connected to a tube 1080. The tube 1080 is connected to a tube 1082, which is connected to a tube 1084. The tube 1084 is connected to a tube 1086, which is connected to a tube 1088. The tube 1088 is connected to a tube 1090, which is connected to a tube 1092. The tube 1092 is connected to a tube 1094, which is connected to a tube 1096. The tube 1096 is connected to a tube 1098, which is connected to a tube 1100. The tube 1100 is connected to a tube 1102, which is connected to a tube 1104. The tube 1104 is connected to a tube 1106, which is connected to a tube 1108. The tube 1108 is connected to a tube 1110, which is connected to a tube 1112. The tube 1112 is connected to a tube 1114, which is connected to a tube 1116. The tube 1116 is connected to a tube 1118, which is connected to a tube 1120. The tube 1120 is connected to a tube 1122, which is connected to a tube 1124. The tube 1124 is connected to a tube 1126, which is connected to a tube 1128. The tube 1128 is connected to a tube 1130, which is connected to a tube 1132. The tube 1132 is connected to a tube 1134, which is connected to a tube 1136. The tube 1136 is connected to a tube 1138, which is connected to a tube 1140. The tube 1140 is connected to a tube 1142, which is connected to a tube 1144. The tube 1144 is connected to a tube 1146, which is connected to a tube 1148. The tube 1148 is connected to a tube 1150, which is connected to a tube 1152. The tube 1152 is connected to a tube 1154, which is connected to a tube 1156. The tube 1156 is connected to a tube 1158, which is connected to a tube 1160. The tube 1160 is connected to a tube 1162, which is connected to a tube 1164. The tube 1164 is connected to a tube 1166, which is connected to a tube 1168. The tube 1168 is connected to a tube 1170, which is connected to a tube 1172. The tube 1172 is connected to a tube 1174, which is connected to a tube 1176. The tube 1176 is connected to a tube 1178, which is connected to a tube 1180. The tube 1180 is connected to a tube 1182, which is connected to a tube 1184. The tube 1184 is connected to a tube 1186, which is connected to a tube 1188. The tube 1188 is connected to a tube 1190, which is connected to a tube 1192. The tube 1192 is connected to a tube 1194, which is connected to a tube 1196. The tube 1196 is connected to a tube 1198, which is connected to a tube 1200. The tube 1200 is connected to a tube 1202, which is connected to a tube 1204. The tube 1204 is connected to a tube 1206, which is connected to a tube 1208. The tube 1208 is connected to a tube 1210, which is connected to a tube 1212. The tube 1212 is connected to a tube 1214, which is connected to a tube 1216. The tube 1216 is connected to a tube 1218, which is connected to a tube 1220. The tube 1220 is connected to a tube 1222, which is connected to a tube 1224. The tube 1224 is connected to a tube 1226, which is connected to a tube 1228. The tube 1228 is connected to a tube 1230, which is connected to a tube 1232. The tube 1232 is connected to a tube 1234, which is connected to a tube 1236. The tube 1236 is connected to a tube 1238, which is connected to a tube 1240. The tube 1240 is connected to a tube 1242, which is connected to a tube 1244. The tube 1244 is connected to a tube 1246, which is connected to a tube 1248. The tube 1248 is connected to a tube 1250, which is connected to a tube 1252. The tube 1252 is connected to a tube 1254, which is connected to a tube 1256. The tube 1256 is connected to a tube 1258, which is connected to a tube 1260. The tube 1260 is connected to a tube 1262, which is connected to a tube 1264. The tube 1264 is connected to a tube 1266, which is connected to a tube 1268. The tube 1268 is connected to a tube 1270, which is connected to a tube 1272. The tube 1272 is connected to a tube 1274, which is connected to a tube 1276. The tube 1276 is connected to a tube 1278, which is connected to a tube 1280. The tube 1280 is connected to a tube 1282, which is connected to a tube 1284. The tube 1284 is connected to a tube 1286, which is connected to a tube 1288. The tube 1288 is connected to a tube 1290, which is connected to a tube 1292. The tube 1292 is connected to a tube 1294, which is connected to a tube 1296. The tube 1296 is connected to a tube 1298, which is connected to a

is shown to include a housing 28 and a hydrodynamic heater cap 30 fixedly attached to the housing. Hydrodynamic heater cap 30 is also viewable in FIGS. 3 and 8. Hydrodynamic heater housing 28 and hydrodynamic heater cap 30 together define an interior fluid cavity 32. Disposed within interior cavity 32 is a stator 34 and a coaxially aligned rotor 36 positioned adjacent stator 34. Stator 34 may be fixedly attached to hydrodynamic heater housing 28. Rotor 36 may be mounted on a drive shaft 38 for concurrent rotation therewith about an axis 40. Stator 34 and rotor 36 define annular cavities 42 and 44, respectively, which together define a hydrodynamic chamber 46. Fluid heating occurs within hydrodynamic chamber 46. The heated fluid may be transferred between hydrodynamic heater 22 and heat exchanger 24 through passages in manifold 26.

Power for rotatably driving rotor 36 may be supplied by any of a variety of power sources, including but not limited to an engine of the vehicle in which the supplemental heating system is installed. An end of drive shaft 38 extends from hydrodynamic heater housing 28. Fixedly attached to the end of drive shaft 38 is a drive means 48, which may include a pulley 50 engageable with, for example, an engine accessory drive belt. The accessory drive belt may in turn engage an accessory drive attached to a crankshaft of the vehicle engine. The accessory drive belt transfers torque generated by the engine to drive shaft 38 connected to rotor 36. It is also contemplated that drive shaft 38 may be alternatively driven by another suitable means, such as an electric motor.

Drive means 48 may include a clutch, which may, for example and without limitation, be an electromagnetic clutch. The clutch may be selectively engaged in response to the particular heating requirements of the system. The clutch may be operated to disengage rotor 36 from the power supply when no additional heating of the fluid is required, which may be desirable, for example, to minimize the power being drawn from the vehicle engine for improving engine efficiency and to help maximize the amount of power available for other uses, such as propelling the vehicle.

Referring also to FIG. 3, heat exchanger 24 may include a generally cylindrically shaped housing 52 that engages an outer circumference 54 of hydrodynamic heater cap 30 and is fixedly secured to hydrodynamic heater housing 28. Hydrodynamic heater cap 30 has a generally outwardly convex shape that extends into heat exchanger housing 52 when heat exchanger housing 52 is attached to hydrodynamic heater housing 28. Outer circumference 54 of the hydrodynamic heater cap 30 may have a slightly smaller diameter than an interior diameter 55 of heat exchanger housing 52 to provide a pilot for positioning the heat exchanger housing relative to the hydrodynamic heater housing. A forward end 57 of heat exchanger housing 52 may include a circumferential notch 56 for receiving an o-ring 58. For clarity, o-ring 58 is not shown in FIG. 3, but is shown in FIG. 2. O-ring 58 forms a seal between heat exchanger housing 52 and hydrodynamic heater housing 28 when the two components are connected together.

Attached to an end 60 of heat exchanger housing 52 is an end cap 62. End 60 of heat exchanger housing 52 includes a circumferential o-ring notch 64. An o-ring 66 is positioned within notch 64 to form a seal between heat exchanger housing 52 and end cap 62. For clarity, o-ring 66 is not shown in FIG. 3, but is shown in FIG. 2.

One or more threaded studs 68 and nuts 70 may be used to secure end cap 62 and heat exchanger housing 52 to hydrodynamic heater housing 28. Studs 68 extend through axial holes 72 (see also FIG. 5) formed in a wall 74 of heat exchanger housing 52, and engage a corresponding threaded

hole 76 (see also FIG. 8) in hydrodynamic heater housing 28. Attached to an opposite end 78 of stud 68 is nut 70.

With reference also to FIGS. 3-8, heat exchanger housing 52, hydrodynamic heater cap 30 and heat exchanger end cap 62 together define an internal fluid cavity 80. Positioned within fluid cavity 80 is a heat exchanger core 82. Heat exchanger core 82 includes a plurality of spaced apart elongated tubes 84. The longitudinal axis of tubes 84 are arranged generally parallel to a longitudinal axis of heat exchanger housing 52. With particular reference to FIG. 6, an end 86 of each of the tubes 84 engages a corresponding aperture 88 in a heat exchanger core forward end plate 90, and an opposite end 92 engages a corresponding aperture 94 in a heat exchanger core rear end plate 96. Tubes 84 may be secured to heat exchanger core end plates 90 and 96 by any suitable means, including but not limited to, welding, brazing, soldering, crimping and adhesives. Heat exchanger core forward end plate 90 and heat exchanger core rear end plate 96 are oriented generally perpendicular to the longitudinal axis of tubes 84.

With reference to FIG. 4, an outer edge 98 of heat exchanger core forward end plate 90 includes a circumferential o-ring groove 100. An o-ring 102 engages the o-ring groove to form a seal between heat exchanger housing 52 and forward heat exchanger end plate 90 when the heat exchanger core is installed in housing 52.

With reference to FIG. 3, heat exchanger core 82 is located within heat exchanger housing 52 by means of a flange 104 that extends radially outward from an outer edge 106 of heat exchanger core rear end plate 96. The flange is trapped between end 60 of heat exchanger housing 52 and end cap 62.

Referring to FIGS. 4-7, heat exchanger core 82 may employ one or more baffles to direct the heated fluid received from hydrodynamic heater 22 over the outer surface of tubes 84. A vertical baffle 108 divides heat exchanger core 82 into two halves. Vertical baffle 108 extends widthwise between heat exchanger core forward end plate 90 and heat exchanger core rear end plate 96, and lengthwise between diametrically opposed sides of an inner surface 110 of heat exchanger housing 52. As shown in FIG. 5, heated fluid from hydrodynamic heater 22 (represented by the arrows in FIG. 5) flows downward through one side of heat exchanger core 82 and up through the opposite side. A notched region 112, located at the bottom of vertical baffle 108, allows fluid to pass between the two sides of the heat exchanger core.

One or more horizontal baffle plates may also be provided for directing the heated fluid from hydrodynamic heater 22 over the outside surface of tubes 84. By way of example, heat exchanger core 82 may include a total of six horizontal baffles positioned on opposite sides of vertical baffle 108 (three baffles per side). A pair of middle horizontal baffles 114 are arranged on opposite sides of vertical baffle 108 and extend radially outward from a proximate center of the vertical baffle. Middle horizontal baffles 114 extend widthwise between heat exchanger core forward end plate 90 and heat exchanger core rear end plate 96, and lengthwise between vertical baffle 108 and inner surface 110 of heat exchanger housing 52. A pair of upper horizontal baffles 116 are arranged on opposite sides of vertical baffle 108, and extend generally parallel to middle baffles 114. Upper horizontal baffles 116 extend widthwise between heat exchanger core forward end plate 90 and heat exchanger core rear end plate 96, and lengthwise between vertical baffle 108 and inner surface 110 of heat exchanger housing 52. A pair of lower horizontal baffles 118 are arranged on opposite sides of vertical baffle 108 and extend generally parallel to middle baffles 114. Lower horizontal baffles 118 extend widthwise between heat exchanger core forward end plate 90 and heat exchanger core rear end plate 96, and lengthwise between vertical baffle 108 and inner surface 110 of heat exchanger housing 52.

A pair of upper horizontal baffles 116 are arranged on opposite sides of vertical baffle 108, and extend generally parallel to middle baffles 114. Upper horizontal baffles 116 extend widthwise between heat exchanger core forward end plate 90 and heat exchanger core rear end plate 96, and lengthwise between vertical baffle 108 and inner surface 110 of heat exchanger housing 52. A pair of lower horizontal baffles 118 are arranged on opposite sides of vertical baffle 108 and extend generally parallel to middle baffles 114. Lower horizontal baffles 118 extend widthwise between heat exchanger core forward end plate 90 and heat exchanger core rear end plate 96, and lengthwise between vertical baffle 108 and inner surface 110 of heat exchanger housing 52.

core rear end plate 96, and lengthwise between vertical baffle 108 and inner surface 110 of heat exchanger housing 52.

Upper horizontal baffles 116, middle horizontal baffles 114, and lower horizontal baffles 118 each include a notched region arranged adjacent one of the heat exchanger core end plates 90 and 96. For example, upper horizontal baffles 116 include a notched region 120 positioned adjacent heat exchanger core rear end plate 96; middle horizontal baffles 114 include a notched region 122 positioned adjacent heat exchanger core forward end plate 90; and lower horizontal baffles 118 include a notched region 124 positioned adjacent heat exchanger core rear end plate 96. As shown in FIG. 6, the notched regions allow heated fluid from hydrodynamic heater 22 (represented by the arrows in FIG. 6) to flow around the horizontal baffles as the fluid flows down one side of the heat exchanger core and up the opposite side. Staggering the notched regions of adjacent horizontal baffles causes the heated fluid to travel along a generally back and forth path between heat exchanger core forward end plate 90 and heat exchanger core rear end plate 96 as the fluid travels down one side of the heat exchanger core and up the opposite side, as shown in FIGS. 5 and 6.

With reference to FIGS. 3-9, supplemental heating system 20 may be fluidly connected to a fluid supply source, such as an automotive cooling system, through an inlet port 126 and an outlet port 128. Fluid may be transferred from the vehicle cooling system to supplemental heating system 20 through inlet port 126 and returned to the cooling system through outlet port 128. Fluid entering supplemental heating system 20 through inlet port 126 is discharged into an inlet plenum 129. Fluid discharged from supplemental heating system 20 accumulates in an outlet plenum 131 prior to passing through outlet port 128. A plenum baffle 132 fluidly separates inlet plenum 129 from outlet plenum 131.

At least a portion of the fluid entering supplemental heating system 20 through inlet port 126 passes through tubes 84 that are fluidly connected to inlet plenum 129. The fluid picks up heat from the heated fluid discharged from hydrodynamic heater 22 as it passes over the outside of the tubes. The fluid is discharged from tubes 84 into an intermediate plenum 133 located between heat exchanger core front end plate 90 and hydrodynamic heater cap 30. Additional heat may also be transferred from hydrodynamic heater 22 through hydrodynamic heater cap 30 to the fluid passing through intermediate plenum 133. To promote heat transfer between hydrodynamic heater 22 and heat exchanger 24, hydrodynamic heater cap 30 may be constructed from a thermally conductive material. The fluid travels from intermediate plenum 133 through tubes 84 that are fluidly connected to outlet plenum 131, where the fluid picks up additional heat from the heated fluid flowing over the tubes. The fluid then discharges into outlet plenum 131, from which point the fluid flows out though outlet port 128 and back to the source of the fluid, for example, the vehicle cooling system.

With reference to FIG. 9, hydrodynamic chamber 46 of hydrodynamic heater 22 may be fluidly connected to the fluid supply source, for example, the engine cooling system, through inlet port 126. Fluid from the cooling system travels from inlet plenum 129 through a hydrodynamic chamber supply passage 130 and discharges into a hollow cavity 134 formed between the back of rotor 36 and hydrodynamic heater cap 30. One or more rotor passages 136 fluidly connect cavity 134 to hydrodynamic chamber 46. Rotor passage 136 extends through a blade 138 of rotor 36, and has one end fluidly connected to cavity 134 and an opposite end to hydrodynamic chamber 46.

Fluid present in hydrodynamic chamber 46 travels along a generally toroidal path within the chamber, absorbing heat as the fluid travels between annular cavities 42 and 44 of stator 34 and rotor 36, respectively. Heated fluid exits hydrodynamic chamber 46 through one or more discharge orifices 140 located along a back wall 142 of stator 34 near its outer circumference. Orifice 140 may be fluidly connected to a circumferential annulus 144 formed between hydrodynamic heater housing 28 and a back wall of stator 34. A hydrodynamic heater discharge port 145 fluidly connects annulus 144 to a hydrodynamic heater discharge passage 146 formed in manifold 26. Fluid exiting hydrodynamic chamber 46 through orifice 140 travels through discharge passage 146 to a heat exchanger inlet port 148 (see also FIG. 5). Fluid exits heat exchanger inlet port 148 and travels through heat exchanger core 82 in the manner generally shown in FIGS. 5 and 6. Generally speaking, the fluid passing over the outside of tubes 84 (i.e., the heated fluid discharged from hydrodynamic heater 22) is at a higher pressure than the fluid supply source, and the fluid flowing through tubes 84 and intermediate plenum 133 is at a lower pressure than the fluid over the outside of the tubes. At least a portion of the heat from the heated fluid is transferred to the fluid passing through tubes 84. The fluid exits heat exchanger 24 through a heat exchanger discharge port 150, shown in FIG. 5, and is directed back to hydrodynamic heater 22 through a return passage 152 formed in manifold 26. Manifold return passage 152 is fluidly connected to a hydrodynamic heater inlet port 153. Fluid entering the hydrodynamic heater through inlet port 153 passes through a hydrodynamic chamber return passage 154 formed in hydrodynamic heater housing 28. The fluid discharges from hydrodynamic chamber return passage 154 into an annular plenum 156 in hydrodynamic heater housing 28. The fluid enters hydrodynamic chamber 46 at an inner circumference 158 of the hydrodynamic chamber.

Manifold 26 may be constructed from any of a variety of generally inelastic materials, including but not limited to metals, plastics, and composites. Indeed, it may be desirable that substantially the entire fluid path between hydrodynamic heater discharge port 145 and heat exchanger inlet port 148 (i.e., discharge passage 146), and substantially the entire fluid path between heat exchanger discharge port 150 and hydrodynamic heater inlet port 153 (i.e., return passage 152), is constructed from an inelastic material. This may substantially reduce or eliminate difficulties in controlling the operation of hydrodynamic heater 22 that may arise when a generally elastic material is used in forming the fluid pathways between hydrodynamic heater 22 and heat exchanger 24.

Continuing to refer to FIG. 9, a control valve 160 (see also FIG. 1) controls the pressure occurring within hydrodynamic chamber 46, and consequently the corresponding heat output. An inlet port 162 of control valve 160 is fluidly connected to manifold return passage 152 through a control valve inlet passage 164, and an outlet port 166 is fluidly connected to intermediate plenum 133 of heat exchanger 24 through a control valve outlet passage 168. The pressure occurring within intermediate plenum 133 is generally lower than the pressure occurring within manifold return passage 152. Control valve 160 operates to selectively transfer a portion of the fluid passing through manifold return passage 152 to intermediate plenum 133. This reduces the amount of fluid returned to hydrodynamic chamber 46, thereby reducing the pressure occurring within the hydrodynamic chamber and its corresponding heat output.

With regard to the processes, systems, methods, etc. described herein, it should be understood that, although the steps of such processes, etc. have been described as occurring

according to a certain ordered sequence, such processes could be practiced with the described steps performed in an order other than the order described herein. It further should be understood that certain steps could be performed simultaneously, that other steps could be added, or that certain steps described herein could be omitted. In other words, the descriptions of processes herein are provided for the purpose of illustrating certain embodiments, and should in no way be construed so as to limit the claimed invention.

It is to be understood that the above description is intended to be illustrative and not restrictive. Many embodiments and applications other than the examples provided would be apparent to those of skill in the art upon reading the above description. The scope of the invention should be determined, not with reference to the above description, but should instead be determined with reference to the appended claims, along with the full scope of equivalents to which such claims are entitled. It is anticipated and intended that future developments will occur in the arts discussed herein, and that the disclosed systems and methods will be incorporated into such future embodiments. In sum, it should be understood that the invention is capable of modification and variation and is limited only by the following claims.

All terms used in the claims are intended to be given their broadest reasonable constructions and their ordinary meanings as understood by those skilled in the art unless an explicit indication to the contrary is made herein. In particular, use of the singular articles such as "a," "the," "said," etc. should be read to recite one or more of the indicated elements unless a claim recites an explicit limitation to the contrary.

What is claimed is:

1. A heating apparatus connectable to a fluid supply source that supplies a fluid to be heated, the heating apparatus comprising:

a hydrodynamic heater including a hydrodynamic chamber disposed within an interior cavity of the hydrodynamic heater, the hydrodynamic chamber operable for selectively heating the fluid present within the hydrodynamic chamber when the heating apparatus is connected to the fluid supply source, the hydrodynamic heater having an inlet port and a discharge port;

a heat exchanger fluidly connected to the inlet port and the discharge port of the hydrodynamic heater, the heat exchanger including a heat exchanger core disposed within an interior cavity of the heat exchanger; and

a wall at least partially defining the interior cavity of the hydrodynamic heater and the interior cavity of the heat exchanger.

2. The heating apparatus of claim 1 further comprising a manifold having a discharge passage fluidly connecting the discharge port of the hydrodynamic heater to an inlet port of the heat exchanger, and a return passage fluidly connecting a discharge port of the heat exchanger to the inlet port of the hydrodynamic heater.

3. The heating apparatus of claim 2, wherein the return passage is selectively fluidly connectable to a region of the interior cavity of the heat exchanger having a lower pressure than the pressure within the return passage.

4. The heating apparatus of claim 3 further comprising a valve operable to selectively fluidly connect the return passage to the interior cavity of the heat exchanger.

5. The heating apparatus of claim 2, wherein the manifold is constructed from a substantially inelastic material.

6. The heating apparatus of claim 1, wherein the heat exchanger includes a first region receiving fluid from the hydrodynamic heater and a second region receiving fluid from the fluid supply source, the second region fluidly con-

nected to the wall that at least partially defines the interior cavity of the hydrodynamic heater and the interior cavity of the heat exchanger, and the first region fluidly disconnected from the wall.

5 7. The heating apparatus of claim 6, wherein at least a portion of the second region is disposed between the first region and the wall.

10 8. The heating apparatus of claim 1 further comprising a hydrodynamic heater housing at least partially defining the interior cavity of the hydrodynamic heater, and a heat exchanger housing at least partially defining the interior cavity of the heat exchanger, wherein the heat exchanger housing is attached to the hydrodynamic heater housing.

15 9. The heating apparatus of claim 1, wherein the wall is thermally conductive.

10 10. A heating apparatus connectable to a fluid supply source that supplies a fluid to be heated, the heating apparatus comprising:

20 a hydrodynamic heater including a hydrodynamic chamber disposed within an interior cavity of the hydrodynamic heater, the hydrodynamic chamber operable for selectively heating the fluid present within the hydrodynamic chamber when the heating apparatus is connected to the fluid supply source, the hydrodynamic heater having an inlet port and a discharge port;

a heat exchanger having an inlet port and a discharge port, the heat exchanger including a heat exchanger core disposed within an interior cavity of the heat exchanger; and

30 a manifold having a discharge passage fluidly connecting the discharge port of the hydrodynamic heater to an inlet port of the heat exchanger, and a return passage fluidly connecting a discharge port of the heat exchanger to the inlet port of the hydrodynamic heater; and a wall at least partially defining the interior cavity of the hydrodynamic heater and the interior cavity of the heat exchanger.

35 11. The heating apparatus of claim 10, wherein the manifold is constructed from a substantially inelastic material.

40 12. The heating apparatus of claim 11, wherein the discharge passage is directly connected to the inlet port of the heat exchanger and the discharge port of the hydrodynamic heater, and the return passage is directly connected to the discharge port of the heat exchanger and the inlet port of the hydrodynamic heater.

45 13. The heating apparatus of claim 11, wherein substantially an entire fluid path between the discharge port of the hydrodynamic heater and the inlet port of the heat exchanger, and between the discharge port of the heat exchanger and the inlet port of the hydrodynamic heater is constructed from a substantially inelastic material.

50 14. The heating apparatus of claim 10, wherein the return passage is selectively fluidly connectable to a region of the interior cavity of the heat exchanger having a lower pressure than the pressure within the return passage.

55 15. The heating apparatus of claim 14 further comprising a valve operable to selectively fluidly connect the return passage to the interior cavity of the heat exchanger.

60 16. A heating apparatus connectable to fluid supply source that supplies a fluid to be heated, the heating apparatus comprising:

a hydrodynamic heater including a hydrodynamic chamber disposed within an interior cavity of the hydrodynamic heater, the hydrodynamic chamber operable for selectively heating the fluid present within the hydrodynamic chamber when the heating apparatus is connected to the

- fluid supply source, the hydrodynamic heater having an inlet port and a discharge port;
- a heat exchanger having an inlet port and a discharge port;
- a discharge passage directly fluidly connecting the discharge port of the hydrodynamic heater to the inlet port of the heat exchanger;
- a return passage directly fluidly connecting the discharge port of the heat exchanger to the inlet port of the hydrodynamic hydrodynamic heater; a wall at least partially defining the interior cavity of the hydrodynamic heater and an interior cavity of the heat exchanger; and
- wherein substantially the entire discharge passage and the return passage are constructed from a substantially inelastic material.
17. The heating apparatus of claim 16 further comprising a heat exchanger core disposed within the interior cavity of the heat exchanger.
18. The heating apparatus of claim 17, wherein the return passage is selectively fluidly connectable to a region of the interior cavity of the heat exchanger having a lower pressure than the pressure within the return passage.
19. The heating apparatus of claim 18 further comprising a valve operable to selectively fluidly connect the return passage to the interior cavity of the heat exchanger.
